CAN OPENER WITH RESILIENT CAN BEAD
GRIPPING MEMBER

Charles D. Tuccori, Chicago, Ill.

Application December 20, 1951, Serial No. 262,563

10 Claims. (CL 30—15)

1

This invention relates to a can opener. More specifically the invention relates to an improvement in a can opener of the type shown in applicant's Patent 2,551,193, patented May 1, 1951.

In the above patented disclosure an improved can opener includes a knife blade having a pair of laterally spaced gripping elements which grip the bead of a can in secure relation so that a traction wheel can effectively secure traction in moving the knife blade in cutting relation with respect to the can. The gripping elements in this disclosure are formed on a gripping member which is movable with the blade into engagement with the can. Since the blade and gripping elements are integral, it has been found that on occasion the operator may lock the elements into a too rigid or tight engagement with the can thus causing some difficulty in turning the traction wheel. It is a prime object therefore to provide an improved can opener having a blade with laterally spaced gripping elements for firmly though resiliently gripping the can bead of a can.

Another object is to provide a can opener having a blade including a pair of laterally spaced gripping elements which are relatively movable with respect to the blade for resiliently though firmly engaging the bead of a can in a manner designed to prevent rocking of the blade during the can opening operation.

A still further object is to provide a can opener having an improved blade including a clamping member which is relatively movable with respect to the blade, the gripping member including laterally spaced bead gripping elements which are resiliently movable into gripping engagement with a can bead.

A still further object is to provide a can opener having a knife body including a narrow blade projecting from the body, and a gripping or clamping member straddling the narrow blade and having a pair of laterally spaced gripping shoulders or elements on each side of the narrow blade, the opener including springs engaging the gripping elements for urging the same in the direction of movement of the blade during its movement toward engagement with a can, the gripping elements being relatively movable with respect to said blade for resiliently gripping a can bead.

These and further objects will become more readily apparent from a reading of the specification in connection with the accompanying sheet of drawing:

In the drawing:

Figure 1 is a front view in elevation of a can opener;

2

Figure 2 is a side elevational view of a can opener;

Figure 3 is a rear view in elevation of a can opener;

5 Figure 4 is a sectional view of a can opener with a guide member removed, the view being taken generally along line 4—4 of Figure 2.

Figure 5 is a sectional view taken generally along the line 5—5 of Figure 4;

10 Figure 6 is a cross sectional view through a can opener showing the opener in clamping and cutting engagement with a can;

Figure 7 is a fragmentary view of a cutting blade and clamping or gripping member in engagement with a can bead;

15 Figure 8 is a detail front view of a gripping member; and

Figure 9 is a detail plan view of a gripping member.

20 A can opener is generally designated by the reference character 10. The opener 10 includes an upper body portion 11 and a lower body portion 12. The lower body portion 12 supports a traction wheel 13, having a shaft 14 which is journaled in a bore 15. A wing type turning member 16 is rigidly connected to the shaft 14. The lower body portion 12 is provided at its lower end with a laterally projecting supporting lip 17.

25 A blade structure 18 includes a knife body 19 having a narrow cutting blade 20 forming with the body 19 a pair of laterally spaced shoulders 21. The cutting blade 20 is provided at its lower edge with a cutting edge 22. The blade 20 includes a recess or undercut portion 23 as shown in Figure 7, providing a shoulder 24. A gripping or clamping member 25 bridges or straddles the cutting blade 20, the gripping member 25 including laterally spaced gripping elements 26 connected by a bridge member 27 which slides in the recess 23 and engages the shoulder 24 and limits the downward movement of the cutting blade 20 relative to the gripping member 25.

30 The gripping member includes a projecting stud 29 which acts as a stop and which slides in a slot 30 in the cutting blade 20. The bridge 27 is recessed in an arcuate manner as indicated at 31. A gripping member 25 includes a projecting stud 29 which acts as a stop and which slides in a slot 30 in the cutting blade 20. The bridge 27 is recessed in an arcuate manner as indicated at 31. As shown in Figures 4 and 5 a pair of spaced springs 32 engage the shoulders 21 and the gripping member 25 for urging the gripping member in the direction of movement when the cutting blade is moved into engagement with a can top.

35 40 45 50 55 A knife guide in the form of a channel is indicated at 33. The guide 33 includes legs 34 which form guides for the knife body 19. A pin 35 having a handle 36 connected thereto is journaled

3

in a bore 37 of the guide 33, the pin 35 having an eccentric cam 38 rigidly connected thereto. The pin 35 also is journaled in a bore 38' of the upper plate portion 11. The cam is operative to ride in a recess 39 of the knife body 19, the surfaces of the recess in effect being similar to a cam follower.

The guide 33 is formed with projections 40 which extend through openings 41 in the upper plate portion 11. The ends of these projections 40 are riveted over to securely hold the guide 33 in assembled relation with respect to the upper plate portion 11.

In operation the opener 10 is placed in engagement with the can as indicated in Figure 6 and the blade structure 18 is in a retracted position. By rotating the handle 36 the eccentric cam 38 is rotated in the recess 39 and the blade structure 18 is moved downwardly whereupon the cutting blade 20 pierces the upper lid of the can. Simultaneously the clamping member 25 is moved into engagement with the bead of the can and the gripping elements 26 firmly engage the bead. Continued rotation of the handle 36 compresses the springs 32 and move the cutting blade 20 downwardly until the shoulder 24 is spaced slightly from the top of the gripping member 25, whereupon the cutting blade 20 is in proper cutting position.

By virtue of the relative sliding movement of the cutting blade 20 with respect to the clamping member 25 the cutting blade 20 can still be moved after the clamping member has moved into engagement with the can bead. As the cutting blade 20 is thus moved further downwardly, the springs 32 are compressed further thus very firmly holding the gripping elements 26 in clamping engagement with the can bead. By virtue of the resiliency of the springs however movement of the cutting blade 20 to its extreme downward position will not cause binding of the gripping member 25 since the gripping member 25 is held resiliently in engagement with the can bead. In view of the resilient self-adjustability of the gripping member, the can opener is readily adaptable to different height can beads without any adjustment on part of the operator or change in operation.

As best shown in Figures 8 and 9 the bridge member 27 is recessed as indicated at 31, and thus the gripping elements 26 form transversely spaced points of support for supporting the gripping member 25 on the can bead. These spaced points of support are effective to prevent rocking of the opener 10 during the can opening operation.

The stud 29, as indicated in Figure 4 serves as a stop by engaging the lower end of the slot 30, when the blade 20 is retracted, for limiting the downward movement of the gripping member 25 as urged by the springs 32.

It can now be seen that an improved can opener has been disclosed and described, the opener including a cutting blade having a gripping member which is urged resiliently into clamping engagement with a can bead by springs, the clamping member being relatively movable with respect to the cutting blade.

It must be understood that changes and modifications may be made without departing from the spirit of the invention as disclosed, nor the scope thereof as defined in the appended claims.

What I claim is:

1. A can opener comprising an elongated frame having an upper plate portion and a lower plate portion, a toothed traction wheel journaled on

4

the lower plate portion, turning means connected to said toothed traction wheel, a knife guide connected to the upper plate portion, said guide including laterally spaced guide elements, a knife body reciprocally positioned between the guide elements on the upper plate portion, said knife body including a relatively narrow cutting blade projecting from the body and forming therewith a pair of shoulders disposed on laterally opposite sides of said body, a clamping member disposed between said guide elements, said clamping member including a pair of gripping elements disposed on opposite sides of the cutting blade, the gripping member being relatively movable with respect to said cutting blade, resilient members engaging the shoulders of the knife body and said gripping members for urging said gripping members into resilient engagement with a can bead, and means for moving said knife body, said means including a cam connected to the upper plate and movably engaging said knife body.

2. A can opener comprising an elongated frame having an upper plate portion and a lower plate portion, a toothed traction wheel journaled on the lower plate portion, turning means connected to said toothed traction wheel, a knife guide connected to the upper plate portion, said guide including laterally spaced guide elements, a knife body reciprocally positioned between the guide elements on the upper plate portion, said knife body including a relatively narrow cutting blade projecting from the body and forming therewith a pair of shoulders disposed on laterally opposite sides of said body, a clamping member disposed between said guide elements, said clamping member including a pair of gripping elements disposed on opposite sides of the cutting blade, the gripping member being relatively movable with respect to said cutting blade, resilient members engaging the shoulders of the knife body and said gripping members for urging said gripping members into resilient engagement with a can bead, and means for moving said knife body, said means including a cam connected to the upper plate and movably engaging said knife body.

3. A can opener in accordance with claim 2, said cutting blade including a longitudinally extending recess in which said clamping member is disposed for relative longitudinal sliding movement during clamping engagement of the gripping elements with a can bead.

4. A can opener in accordance with claim 2, said clamping member including a connecting bridge member connecting said gripping elements whereby said connecting bridge member and said gripping elements straddle said cutting blade.

5. A can opener in accordance with claim 4, said connecting bridge member having its lower edge recessed to space the same from a can bead during clamping engagement of the gripping elements with a can bead.

6. A can opener comprising an elongated frame having an upper plate portion and a lower plate portion, a toothed traction wheel journaled on the lower plate portion, turning means connected to said toothed traction wheel, laterally spaced guide elements on said upper plate portion, a knife body reciprocally positioned between said guide portions, a knife blade on said body, a pair of gripping elements positioned on laterally opposite sides of said knife blade, said gripping elements being movable with said knife blade into gripping engagement with a can bead, and

being relatively movable with respect to said knife blade, resilient means engaging said gripping elements for urging said gripping elements into clamping engagement with a can bead, and means for moving said knife blade and said gripping elements longitudinally relative to said upper plate portion.

7. A can opener in accordance with claim 6 including stop means between the knife blade and said gripping elements for limiting the relative movement of the gripping elements with respect to said knife blade.

8. For a can opener having a frame and means on the frame for moving a knife blade into cutting and gripping engagement with a can; a knife member comprising a body, a relatively narrower knife blade projecting from said body and forming therewith a pair of oppositely disposed shoulders, said knife blade including a cutting edge at its lower end, a clamping member associated with said knife blade and being longitudinally movable with respect thereto, said clamping member including a pair of gripping elements disposed on opposite sides of said cutting blade, and springs engaging said shoulders 25

and said gripping elements for continually urging the gripping elements in the direction of said cutting edge.

9. For a can opener in accordance with claim 8, said clamping member including a connecting bridge member straddling said knife blade and connecting said gripping elements.

10. For a can opener in accordance with claim 9, wherein said connecting bridge member has its lower edge recessed with respect to the surfaces of the gripping elements which are adapted to engage a can bead in clamping relation.
